UNITED STATES PATENT OFFICE

WILLIAM A. AMES, OF HORNELL, NEW YORK

INCANDESCENT BULB SHADE STRUCTURE

Application filed November 21, 1930. Serial No. 497,306.

This invention relates to an improved reflector shade construction for use and association with a conventional incandescent electric lamp of the type universally employed in industrial plants to afford artificial lighting means for workers, and it has more particular reference to a structure to which is expressly, but not necessarily, designed for use in a textile mill.

It is a matter of common knowledge, to persons skilled in the art to which the invention relates, that lighting facilities are frequently inefficient and this is generally due to the fact that the electric bulbs affording the source of light are generally suspended or hung at points remote from the weaving machine. This is objectionable because the light beams and rays are projected in an irregular fashion on the cloth, thus resulting in the development of objectionable shadows, such as interfere with proper inspection of the cloth during manufacture.

Electric suspension cords generally employed in association with the bulb are in plants of this character subject to rapid deterioration because of excessive moisture and this causes the cords to rot and produces short circuits. Moreover, as the lights are generally not rigidly supported, they are susceptible to unusual and undesirable swinging rather loosely, then too, because of the distant relationship of the bulbs to the machines and cloth, strong wattage bulbs are required. This promotes unnecessary expense of illumination.

Some attempts have been made to provide various shock absorbing means for these remote suspended lights, and sometimes the lights are mounted on the machine. Owing to excessive vibration however, lights mounted on the machine and rigidly attached as they usually are, are subject to undue vibration and subsequent destruction.

The purpose of the present invention is to provide a simple and economical lighting fixture which is characterized primarily by a unique type of shade whose function is to provide a shadow-proof reflector.

A feature of the invention is predicated upon the use of a rectangular box-like in-

verted shade which is yieldably suspended direct from the machine in close proximity to the cloth, whereby to project the light rays and beams intimately against the cloth.

Additional novelty is founded on the usage of elastic suspension springs permitting the device to be yieldably suspended directly from the machine at the desired point with respect to the cloth.

A still further feature of the invention is dependent upon the utilization of a rectangular reflector or shade and an associated frusto-conical canopy which is associated with the shade and located off-center so as to equalize and render uniform the distribution of light rays and to minimize the development of objectionable shadows.

Other features and advantages will become more readily apparent from the following description and drawings. In the drawings:

Figure 1 is a front elevational view of a device constructed in accordance with the present inventive conception.

Figure 2 is a bottom view thereof.

Figure 3 is an end view.

Figure 4 is a sectional view showing the relative mechanical relationship of the features of the casing or shade.

The shade in the drawings is generally designated by the reference character 5 and it is constructed of appropriate material. As before stated, it is of general rectangular box-like form and the four walls thereof are spaced and parallel with respect to each other. The top 6 as seen in Figure 4 is of concavo-convex formation, the curvature being in an upward direction. At an offset point, this top is provided with a circular hole to accommodate the canopy 7. This canopy is also of suitable material and of frusto-conical configuration. The top edge is formed with a marginal annular bead 8 to accommodate the retaining set screws 9 for the apertured bulb suspension disc 10.

This disc is provided with a centralized screw-threaded mounting collar or ring 11 engageable with the threads on the conventional socket 12. The socket contains the incandescent electric bulb 13. The numeral 14 merely designates the electric current supply.

cord or cable. The marginal flange of the disc 10 surrounds the bead 8 and carries the set screws which are engageable beneath the bead to hold the parts in assembled position.

5 One-half portion 15 of this canopy is somewhat shorter in length than the remaining half portion 16. The flanged inner end 17 cooperates with the underside of the reflecting surface of the top 6 as shown in Figure 4.

10 This canopy 7 has swivel or rotatable connection with the top 6 so that it can be turned with respect to the latter details to regulate the light beams.

15 The numeral 18 in Figure 1 designates an apertured attaching lug which is used when the shade is attached to a vibrationless machine. At the four corners are additional apertured ears or lugs 19 which serve to accommodate coiled suspension or hanger springs 20. These springs are rigidly attached to existing parts 21 of the textile machine. This therefore allows the device to be yieldably suspended directly from the machine in close proximity to the cloth to permit inspection of 25 the texture as the operation of weaving is carried on.

It might also be mentioned that the marginal lower end portions of the walls of the casings or shade are rolled as at 22 and these 30 contain a reinforcing wire to render the structure rigid and sturdy.

35 It is thought that the description taken in connection with the drawings will enable a clear understanding of the invention to be had. Therefore, a more lengthy description is thought unnecessary. While the preferred embodiment of the invention has been shown and described, it is to be understood that minor changes coming within the field of invention claimed may be resorted to if desired.

40 I claim:

45 1. As a new product of manufacture, an incandescent electric bulb shade comprising a longitudinally elongated substantially rectangular open bottom box-like casing of a comparatively shallow depth including plane spaced parallel side and end walls, and an upwardly arched concavo-convex top, said top being formed at a point off center with an 50 opening to accommodate a source of illumination, and a frusto-conical canopy located in said opening and provided at its top with bulb supporting means.

55 2. In a structural assembly of the class described, in combination, a casing comprising a rectangular body including straight parallel end and side walls, and a curvate top, said top being provided with an opening located off center, a frusto-conical canopy having a flange 60 at its bottom, the lower end portion of said canopy extending through said opening and said flange being in contact with the under side of said curvate top, the upper portion of the canopy projecting above said top and 65 formed with an annular outstanding retaining

ing bead, and a bulb clamp including a flanged marginal portion provided with set screws for detachable engagement with said bead.

In testimony whereof I affix my signature. 70
WILLIAM A. AMES.
